UNITED STATES PATENT OFFICE

170,502

COMEDY FIGURE

Ralph W. Kayser, Beverly Hills, Calif., assignor to Hy-G Products Co., Los Angeles, Calif.

Application April 27, 1953, Serial No. 24,696

Term of patent 3½ years

(Cl. D34—4)

To all whom it may concern:

Be it known that I, Ralph W. Kayser, a citizen of the United States, residing in the city of Beverly Hills, in the county of Los Angeles and State of California, have invented a new, original, and ornamental Design for a Comedy Figure, of which the following is a specification, reference being had to the accompanying drawing forming part thereof.

Fig. 1 is a side elevation of a comedy figure, showing my new design.

Fig. 2 is a front elevation thereof, and

Fig. 3 is a forwardly tilted rear elevation thereof.

I claim:

The ornamental design for a comedy figure, substantially as shown.

RALPH W. KAYSER.
